Primary Examiner — John Windmuller(74) *Attorney, Agent, or Firm* — Ohlandt, Greeley, Ruggiero & Perle, L.L.P.(57) **CLAIM**

The ornamental design for an antenna ball joint mount, as shown and described.

DESCRIPTION

FIG. 1 is a front perspective view of an antenna ball joint mount according to the present disclosure;

FIG. 2 is a rear perspective view of the antenna ball joint mount of FIG. 1;

FIG. 3 is a front view of the antenna ball joint mount of FIG. 1;

FIG. 4 is a rear view of the antenna ball joint mount of FIG. 1;

FIG. 5 is a first side view of the antenna ball joint mount of FIG. 1;

FIG. 6 is a second, opposite side view of the antenna ball joint mount of FIG. 1;

FIG. 7 is a top view of the antenna ball joint mount of FIG. 1; and,

FIG. 8 is a bottom view of the antenna ball joint mount of FIG. 1.

The broken lines in the drawings illustrating form no part of the claimed design.

1 Claim, 8 Drawing Sheets(56)
